CHILDREN'S PLAY TABLE

Forrest F. Caster, 2723 S. 37th St., Kansas City, Kans.
Filed Oct. 17, 1962, Ser. No. 231,136
4 Claims. (Cl. 272—33)

This invention relates to new and useful improvements in play equipment for children, and has particular reference to that class of play device comprising a table with a chair or seat attached thereto.

The principal object of the present invention is the provision of a play table which is circular and having a chair or seat attached thereto for rotation about the central vertical axis of the table, whereby a child in the seat may pull or push himself around the table to gain ready access to any portion of the surface thereof. If desired, various types of toys may be permanently affixed to the table.

Another object is the provision of a play table of the character described having novel means for resisting rotation of the seat and to hold it releasably at any angular position at which it may come to rest, whereby both to prevent too easy rotation which might be troublesome or annoying to the child, and also to provide healthful exercise for the child in pushing or pulling the chair around the table.

Another object is the provision of a play table of the character described having means for adjusting the effective diameter of the table base, whereby to prevent the table from being overturned by the weight of heavier children sitting in the seat.

A still further object is the provision of a play table of the character described wherein the elevation of the seat and the table top are independently adjustable to adapt the device for use by children of different ages and heights.

Other objects are simplicity and economy of construction, efficiency and dependability of operation, easy portability from place to place, and adaptability for use in a wide variety of applications.

With these objects in view, as well as other objects which will appear in the course of the specification, reference will be had to the accompanying drawing, wherein:

FIG. 1 is a central vertical sectional view of a children's play table embodying the present invention, with parts left in elevation.

FIG. 2 is a fragmentary sectional view taken on line II—II of FIG. 1, with parts broken away, and with the seat rotated slightly from the position shown in FIG. 1.

FIG. 3 is an inverted plan view of the device, with the supporting legs shown in solid lines in their operative positions, and folded to their inoperative positions in dotted lines, and

FIG. 4 is a fragmentary sectional view taken on line IV—IV of FIG. 1.

Like reference numerals apply to similar parts throughout the several views, and the numeral 2 applies to a horizontally disposed table top which is circular and planar, and to the top of which may be secured toys 4 and one or more handles 7, the purpose of which will be discussed hereinafter. The table top is supported above a planar, circular base 6, concentrically therewith, by a vertical standard 8. Said standard comprises a lower tubular member 10 having a flange 12 secured centrally to base 6 by screws 14, and an upper tubular member 16 having a flange 18 at its upper end secured centrally to the lower face of the table top by screws 20. Tubular member 16 is telescoped for vertical sliding movement over tubular member 10, and is releasably secured thereto by a set screw 22, whereby the elevation of table top 2 above base 6 may be adjusted.

Disposed in spaced relation below base 6, and being

2

concentric and of a diameter equal therewith, is a circular track member 24 formed of angle iron, the horizontal leg 26 of said angle iron forming a circular horizontal track, and the vertical leg 28 of said angle iron depending from

5 said track. Base 6 is supported above the track member by a plurality of brackets 30 spaced apart angularly of the base. As shown, there are six such brackets spaced equally around the base. Each of said brackets is substantially L-shaped, being welded or otherwise affixed 10 at their lower ends to track member 24 beneath track leg 26, and being affixed at their upper ends to base 6, as by screws 32. Each of said brackets includes a pair of spaced apart vertical side walls 34 which extend substantially radially to the base.

15 A chair member 36 comprising a seat member 38 and a back 40 is disposed so that a child seated therein is positioned for convenient access to table top 2 and the toys thereon. Said chair is provided with a safety belt 42 for securing a child therein. Preferably the buckle

20 44 or other fastener for securing the safety belt is disposed behind the chair back 40 so that the child will not have ready access thereto. The chair 36 is supported 25 for rotation about the vertical central axis of the table by means including a rod 46 extending radially to stand-

ard 8 intermediate table top 2 and base 6, said rod being secured at its outer end to chair seat 38 by screws 48, and being affixed at its inner end to a circular collar 50 which is rotatably mounted in a groove 52 formed peripherally in a sleeve 54 which is vertically slidable on standard 30 tube 16, and releasably secured thereon by a set screw 56.

Secured to the bottom of chair seat 38 by a flange 58 and screws 60 is a depending vertical tube 62. An L-shaped bar 64 has its vertical leg telescoped slidably within tube 62, and releasably secured therein by set screw 66.

35 The horizontal leg of bar 64 extends inwardly to a point directly above track member 26, and has a horizontal T-head 68 affixed thereto. A cage 70 is affixed to each end of said T-head, and a roller 72 is journaled rotatably in each of said cages. Said rollers have horizontal

40 axes substantially radial to the track, and roll on the upper horizontal surface of the track to further support seat 36. It will be apparent that by loosening set screws 56 and 66, the elevation of seat 36 may be adjusted independently 45 of the elevation of table top 2. This is important since when adjusting the height of the table top for use by a child of any particular height, the corresponding adjustment of chair 36 which is then necessitated is almost never equal to the change of elevation of the table top.

50 A guard plate 74 is disposed horizontally directly beneath seat 38, in coplanar relation to the upper surface of base 6, being secured to bar 64 by suitable brackets 76. The inner edge of said guard plate is arcuate, being concentric with but spaced slightly outwardly from base 6, and the outer edge portion 78 of the guard plate is bent upwardly as shown. The purpose of the guard plate is to

55 prevent any possibility that a child might extend his toes beneath the edge of base 6, where they might be pinched between rollers 72 and track 24.

60 A vertical bolt 80 is rigidly fixed in base 6 in radially inwardly spaced relation from each of brackets 30 attaching track 24 to said base. Said bolts extend downwardly from said base, but to a lesser extent than brackets 30. A rigid, elongated leg 82 is associated with each of 65 said bolts, being provided adjacent one end thereof with a hole 84 (see FIGS. 1 and 2) loosely engaged over said bolt. A helical compression spring 86 is disposed about said bolt, being compressed between said leg and a washer 88 secured on the lower end of said bolt by a nut

70 90. Leg 82 extends radially outwardly from bolt 80, extending beneath track member 24 in an outwardly and downwardly inclined direction, to a point spaced radially

outwardly from the track member. Each leg is provided at its outer end with a wheel 92 journalled rotatably thereto on an axis transverse to the general extent of the leg. Intermediate its ends, each leg 82 is retained between the side walls 34 of the associated bracket 30, whereby pivoting of said leg on its bolt 80 is prevented. Also, a small clip 94 of inverted U-shape (see FIG. 1) is affixed to the upper surface of each leg 82 so as to engage the lower edge of leg 28 of the track member 24, so as to prevent longitudinal forces applied to leg 82 from being transmitted to bolt 80, and also to provide a fulcrum about which leg 82 may pivot in a vertical plane. However, each leg may when desired be pushed downwardly relative to track 24 to disengage it from bracket walls 34 and to disengage clip 94, whereupon said legs may be pivoted inwardly to an inoperative position as shown in dotted lines in FIG. 3, disposed entirely within track 24. In this position the device is supported on floor 96 by track member 24 and the lower edges of bracket walls 32. When the legs are extended as shown in FIG. 1 and in solid lines in FIG. 3, the device is supported on the floor by wheels 92.

In use, a child secured in chair 36 by safety belt 42 may, if the chair and table top elevations have been properly set, propel himself around the table either by pushing with his feet against base 6, or by grasping the table edge or handle 7 with his hands, or both. In this manner he may gain ready access to any portion of the table, or to any of toys 4 thereon. He also greatly enjoys the "merry-go-round" sensation which he thereby creates. In propelling himself around the table, his weight is concentrated at a constantly changing point of the table's periphery. If legs 82 are extended, this shifting of his weight causes the legs closest to him to pivot in a vertical plane about clips 94 as fulcrum, the inner ends of said legs being forced downwardly against springs 86. At the same time, the opposite legs pivot in the opposite direction due to the lighter weight supported thereby. Thus the entire table structure, including track 24, is always sloped downwardly toward the child, regardless of the angular position of the chair. The chair is thus always supported on the lowest portion of the track, and movement of the chair requires an "uphill" movement of rollers 72 on the track. This action has several desirable results. Firstly, it provides a "braking" action tending to slow and stop the rotation of the chair once the motivating force has been released. Secondly, it tends to hold the chair in one position after it has stopped. Thirdly, it requires greater effort on the part of the child to rotate the seat, and thus supplies healthful exercise. While table top 2 of course tilts, the degree of tilting is not so great as to affect the utility of the table as such. The degree of tilting can be regulated either by using legs 82 of different lengths, or by using springs 86 of different strengths. Wheels 92 permit the slight horizontal movement of the legs relative to the floor which results from the lever action pivoting of said legs. However, since all of said wheels are disposed on relatively angled axes, they do not permit this device to be rolled generally over the floor, and the device will remain substantially stationary in one position even with legs 82 extended as shown. Nevertheless, the device may be easily transferred from place to place by first folding legs 82 to their inoperative positions as shown in dotted lines in FIG. 3, and turning the entire table on edge so that the circular edges of table top 2, base 6, and track 24 engage the floor. The entire device may then be trundled along like a wheelbarrow, using chair structure 36 as a handle.

For the tilting action described above to occur most

effectively, it will be obvious that the fulcrums of legs 82, as provided by clips 94, should be closer to central standard 8 than the center of chair seat 38. However, the outward extension of legs 82 increases the effective diameter of the base, so that the weight of a heavier child will not tend to overturn the entire assembly. Where the child is of sufficiently light weight to preclude such overturning, or where the tilting action as described is not desired, the legs may be pivoted to their inoperative positions.

While I have shown and described a specific embodiment of my invention, it will be readily apparent that many minor changes of structure and operation could be made without departing from the spirit of the invention as defined by the scope of the appended claims.

What I claim as new and desire to protect by Letters Patent is:

1. A children's play table comprising:
    - a. a circular, generally planar base,
    - b. a standard secured centrally to said base and extending upwardly therefrom,
    - c. a circular table top secured to the upper end of said standard concentrically therewith,
    - d. a chair disposed adjacent the edge of said table top,
    - e. means supporting said chair adjacent the edge of said table top and mounted on said standard for free rotation about the axis thereof, whereby said chair may be rotated around the periphery of said table top,
    - f. a plurality of horizontally extending legs carried by said base, said legs being angularly spaced about the periphery of said base and extending substantially radially thereto, and being outwardly and downwardly inclined to engage the floor at their outer ends to support said base,
    - g. means pivotally connecting each of said legs to said base for pivotal movement in a vertical plane about a horizontal transverse axis intermediate its ends,
    - h. means connecting the inner end of each of said legs to said base for vertical movement relative thereto, and
    - i. resilient means yieldably resisting downward movement of the inner end of each of said legs relative to said base.
  2. A children's play table as recited in claim 1 with the addition of:
    - a. a floor engaging wheel carried rotatably at the outer end of each of said legs.
  3. A children's play table as recited in claim 1 with the addition of:
    - a. a floor engaging wheel carried rotatably at the outer end of each of said legs, the axis of said wheel being horizontal and transverse to the longitudinal extent of said leg.
  4. A children's play table as recited in claim 1 wherein said legs are selectively movable from the position recited to an inoperative position wherein they are disposed entirely above the level of the lower face of said base, whereby said base is supported directly on the floor.
